(57) **CLAIM**

(21) Appl. No.: **29/141,326**

The ornamental design for a retractor for heart valve surgery,
substantially as shown and described.

(22) Filed: **May 4, 2001**

DESCRIPTION

(51) LOC (7) Cl. **24-02**

FIG. 1 is a front isometric view of a retractor for heart valve
surgery showing our new design, with the blades in an open
position.

(52) U.S. Cl. **D24/135**

FIG. 2 is a front elevational view thereof.

(58) Field of Search D24/135; 600/224,

FIG. 3 is a right side elevational view thereof.

600/214, 201, 219, 235, 216, 215

FIG. 4 is a rear elevational view thereof.

(56) **References Cited**

FIG. 5 is a top plan view thereof.

U.S. PATENT DOCUMENTS

FIG. 6 is a bottom plan view thereof; and,

D. 422,705 * 4/2000 Koros et al. D24/135
D. 430,294 * 8/2000 Nathanson et al. D24/135
D. 443,359 * 6/2001 Nathanson et al. D24/135
2,374,863 * 5/1945 Guttmann .

FIG. 7 is a front isometric view thereof, with the blades in
closed position.
